J. F. Heinkel.
ATTORNEY

UNITED STATES PATENT OFFICE.

LEE B. COLE, OF CLEVELAND, OHIO.

HOLDER BRACKET.

Application filed October 19, 1922. Serial No. 595,501.

To all whom it may concern:

Be it known that I, LEE B. COLE, a citizen of the United States, and a resident of Cleveland, county of Cuyahoga, and State 5 of Ohio, have invented a new and useful Improvement in Holder Brackets, of which the following is a specification.

My invention relates to holders and brackets which are adapted to be readily attached 10 to or detached from a support and to readily engage or disengage an object to be held.

The object of my invention is an efficient, simple and inexpensive holder bracket which can readily be attached to or detached from 15 a support without any screws or other auxiliary appliances and without tools, and which can readily engage or disengage an object to be held by the bracket without any auxiliary means or tools.

20 I attain this object by the mechanism shown in the accompanying drawing in which is shown, in a single perspective view, my preferred present construction of a holder bracket adapted to be attached to a 25 telephone and to hold a pencil. The telephone being shown in dot and dash lines.

The holder bracket shown is composed of two halves A and B, which are secured to each other by the rivets 10. Spot-welding 30 or other means may be employed to secure these halves to each other.

It is preferred that these halves be made of tenacious material having spring qualities for the purpose appearing presently.

35 The half A is composed of the body 12 having holes for the rivets 10. The top of this body 12 terminates in the overhanging and arcuate prong 13 adapted to the portion 14 of the telephone C and having the re- 40 versely bent lip 11 extending beyond the center of curvature of the arcuate prong 13 to facilitate the juxtaposition of this prong over the telephone C. The curvature of this arcuate portion of the prong 13 corresponds 45 to the curvature of the portion 14 of the telephone C.

In alignment with the prong 13, the body 12 terminates, at the bottom, in the over- 50 hanging arcuate prong 15 adapted to the portion 17 of the telephone C and having the reversely bent lip 16 extending beyond the center of curvature of the arcuate portion of the prong 15 to facilitate the juxtaposition of the prong 15 over the diametri- 55 cally larger portion 17 of the telephone C. The curvature of this arcuate portion of

the prong 15 corresponds to the curvature of the portion 17 of the telephone C.

On the edge opposite the prongs 13 and 15, the body 12 has the arcuate prong 18 having the reversely bent lip 19 extending beyond the center of curvature of the arcuate portion of the prong 18 to facilitate the insertion of a pencil or other object. The curvature of the arcuate portion of the 65 prong 18 is adapted to a lead pencil or other object to be held by the bracket. The holes 20 are provided to give the holder a better appearance and to permit the prong to take a better grip on the object being held. 70

The half B is composed of the body 21 having holes for the rivets 10 corresponding with the companion holes in the body 12. The top of this body 21 terminates in the overhanging prong 22 having a reversely 75 bent lip and extending beyond the center of curvature of the arcuate portion of the prong 12.

In alignment with the prong 13, the body 21 terminates, at the bottom, in the over- 80 hanging arcuate prong 23 adapted to the portion 17 of the telephone C and having the reversely bent lip 24 extending beyond the center of curvature of the arcuate portion of the prong 23 to facilitate the juxtaposition of the prong 23 over the diametri- 85 cally larger portion 17 of the telephone C. The curvature of the arcuate portion of the prong 23 corresponds to the curvature of the portion 17 of the telephone C. 90

On the edge opposite the prongs 22 and 23, the body 21 has the arcuate prong 25 having the reversely bent lip 26 extending beyond the center of curvature of the arcuate portion of the prong 25 to facilitate the 95 insertion of a pencil or other object similar to the prong 18 and the lip 19. The curvature of the arcuate portion of the prong 25 and the holes 27 are formed and provided for purposes similar to the prong 18 and 100 the holes 20.

When the holder bracket is assembled and attached to the telephone C as shown in the drawing, the prongs 13 and 22 form a pair and encircle more than one half of the dia- 105 metrically smaller portion 14 of the telephone C, and the prongs 15 and 23 form a pair and encircle more than half of the dia- metrically larger portion 17 of the telephone C. 110

Since the ends of the prongs of both pairs extend beyond the centers as set forth, and

since the curvature of prongs correspond to the curvature of the telephone as set forth, the prongs of each pair are closer together at their outer ends than in the middle and 5 the bracket is thereby held in position on the telephone.

Since the bracket is made of material having spring qualities, this narrow end of each 10 pair of prongs can spring over its respective portion of the telephone when the bracket is either attached thereto or detached therefrom.

It being understood that the curvature of 15 the arcuate portions of the prongs correspond to the curvature of its respective portion of the telephone, but that the diametrical distance between the arcuate portions of each pair of prongs, when first made, is less than the diameter of the corresponding part 20 of the telephone so that each pair of prongs will closely hug its respective portion of the telephone.

In order to remove this holder from the 25 telephone, it is preferred that the upper end of the holder be pulled away from the telephone first and that the lower end be pulled away afterward.

It is noted that the openings between the 30 prongs which engage the telephone are at right angles to each other so that the holder can not readily slip off of the telephone.

In order to attach this holder to the telephone, it is preferred that the lower end be pushed over the portion 17 first and that the 35 upper portion be then pushed over the portion 14 afterward. The lips being provided to facilitate the attachment of the holder to the telephone.

The prongs 18 and 25 form a pair and are 40 adapted to partially encircle a pencil or other object to be held and are otherwise formed and operate similar to the prongs which engage the telephone.

A pencil, for instance, may be inserted between the prongs 18 and 25 by placing it between the lips 19 and 26 and pushing it inward until the prongs snap over it and hold it in position. This pencil may be removed 45 from the holder by merely pulling it outward.

In addition to the spring action of the prongs themselves, each of the two halves of the body also exerts a spring action from the rivets 10 outward in each direction so that 50 each half of the body is also flexible to some extent and adapted to enhance the flexibility of the holder and consequently permits the prongs to readily engage or disengage objects of varying sizes.

Having thus described my invention generally as well as particularly in connection with the apparatus shown in the drawings, and without limiting myself to the precise construction shown and described, I claim:—

65 1. A holder bracket of the character de-

scribed, comprising, a body, two pair of prongs projecting from one edge of said body and adapted to engage or disengage the object to which said bracket is to be attached; said two pair of prongs in alignment 70 with each other and the openings thereof angular to each other, and a pair of prongs projecting from the other edge of said body and adapted to engage or disengage the object to be held by said bracket. 75

2. A holder bracket of the character described, comprising, a body, a pair of prongs projecting from one edge of said body and adapted to engage or disengage one portion of the object to which said bracket is to be 80 attached, a pair of prongs projecting from said edge of said body and adapted to engage or disengage a reduced portion of said object and to retain said bracket in longitudinal position on said object, and a pair of 85 prongs projecting from the other edge of said body and adapted to engage or disengage the object to be held by said bracket.

3. A holder bracket of the character described, comprising, a body composed of two halves secured together, prongs projecting from one edge of said halves and adapted to engage or disengage the object to which said bracket is to be attached, said prongs projecting from said one edge forming two pair 90 of prongs in alignment with each other and the openings thereof angular to each other, and prongs projecting from the other edge of said halves and adapted to engage or disengage the object to be held by said bracket. 95

4. A holder bracket of the character described, comprising, a body composed of two halves secured together; each of said halves provided with a prong projecting from one edge at the lower end thereof, with a prong 100 projecting from said edge at the upper end thereof and in angular disposition to the first said prong, and with a prong projecting from the other edge intermediate the ends thereof; said prongs projecting from the 105 first said edges forming two pair of prongs in angular disposition to each other and adapted to engage or disengage the object to which said bracket is to be attached, and said prongs projecting from the second said edges 110 forming a pair of prongs adapted to engage or disengage the object to be held by said bracket. 115

5. A pencil holder bracket for a telephone, comprising, a body, a pair of clamp prongs projecting from said body and adapted to engage or disengage a certain portion of said telephone, a pair of clamp prongs projecting from said body and adapted to engage or disengage a shouldered portion of said telephone to hold said bracket in longitudinal position on said telephone, and a pair of clamp prongs projecting from said body and adapted to engage or disengage said pencil. 120

6. A pencil holder bracket for a telephone, 125

comprising, a body, a pair of clamp prongs projecting from one edge at the lower end of said body and adapted to engage or disengage a larger portion of said telephone, a 5 pair of clamp prongs projecting from said edge at the upper end of said body in angular disposition to the first said pair of prongs and adapted to engage or disengage a re-

duced portion of said telephone to retain said bracket in longitudinal position on said 10 telephone, and a pair of clamp prongs projecting from the other edge of said body intermediate its ends and adapted to engage or disengage said pencil.

LEE B. COLE.
